UNITED STATES PATENT OFFICE.

ALBERT CHRISTIAN OEHRLER, OF PHILADELPHIA, PENNSYLVANIA, ASSIGNOR
TO OEHRLER BROS. & CO.

DESIGN FOR FRINGE.

SPECIFICATION forming part of Design No. 29,349, dated September 13, 1898.

Application filed August 11, 1898. Serial No. 688,402. Term of patent 14 years.

To all whom it may concern:

Be it known that I, ALBERT CHRISTIAN OEHRLER, a citizen of the United States, residing in the city and county of Philadelphia and State of Pennsylvania, have invented and produced a new and original Design for Fringe, of which the following is a specification, reference being had to the accompanying drawings, forming a part thereof.

10 In the accompanying drawings I have illustrated an embodiment of my new design, in which—

Figure 1 is a representation of the obverse side of a section of the fringe, and Fig. 2 is a similar representation of the reverse side of the fringe.

The essential feature of my new design for fringe embodies a gimp or heading from one edge of which depends a series of tufts, and 20 along the lower portion of the gimp or heading, on the obverse side, the fringe-threads are arranged in the form of loops surrounding the tufts, the threads of the loops crossing each other forming substantially inverted-V-shaped upper portions. On the reverse side 25 the threads of the fringe are in parallel

groups, passing through the loops and continuing in the tufts.

Thus, referring to the drawings, A is the strip constituting the gimp or heading of the 30 fringe, and B the tufts extending from the lower edge of the heading A. The fringe-threads C extend, for instance, from the point c' downward around the tufts in the form of a loop c⁵ and upward to the point c², and this 35 configuration is repeated, so that the fringe-threads have the appearance of loops surrounding the tufts, with substantially inverted-V-shaped portions intermediate the loops, and on the reverse side the fringe-threads 40 form parallel groups c⁸, extending through the loops and continuing in the tufts B.

What I claim is—

The design for a fringe, substantially as shown and described.

In testimony whereof I have signed my name to this specification in the presence of two subscribing witnesses.

ALBERT CHRISTIAN OEHRLER.
